UNITED STATES PATENT OFFICE

ERNEST J. BRASSEUR, OF CHICAGO, ILLINOIS, ASSIGNOR TO A. B. DICK COMPANY, OF CHICAGO, ILLINOIS, A CORPORATION OF ILLINOIS.

DUPLICATING APPARATUS.

No. 884,704.

Specification of Letters Patent.

Patented April 14, 1908.

Application filed July 25, 1907. Serial No. 385,433.

To all whom it may concern:

Be it known that I, ERNEST J. BRASSEUR, a subject of the King of Belgium, residing at Chicago, in the county of Cook and State of Illinois, have invented certain new and useful Improvements in Duplicating Apparatus, of which the following is a specification.

This invention relates to duplicating apparatus comprising a printing couple, the members of which are movable relatively to effect the printing of the impression and one of which members is movable toward and away from the other to operative and inoperative positions.

15 The invention has reference more particularly to duplicating apparatus printing by means of a stencil having the characters which are to be reproduced cut therein. In such machines, there are employed a drum 20 having the stencil secured thereon and covering a portion of the periphery, and a pressure-roller adjacent to the drum and movable toward and away from the same to operative and inoperative positions as the drum 25 is rotated. The impression-sheet is fed over a suitable feed-board or guides, so that, when the pressure-roller is raised to operative position, its forward edge will be grasped between the drum and roller and the sheet fed 30 forward and simultaneously imprinted upon. In stencil-duplicating machines employing such a drum and pressure-roller, it is undesirable to have the pressure-roller raised to operative position when no impression-sheet 35 is fed forward to coöperate therewith, for if no sheet were fed forward and the impression-roller were raised, the latter would make contact with the stencil on the drum and take up ink therefrom, and when next an impression- 40 sheet were fed through the machine, this ink would be transferred to the back of the sheet. In accordance with my invention, I provide mechanism for preventing such movements of the pressure-roller into coöperative relation 45 to the drum when no sheet is fed forward thereto. This mechanism coacts with the impression-sheet itself, and its operation is controlled thereby in such manner that if no sheet is present in a position for printing the pressure-roller will not be raised to its operative position.

The preferred embodiment of the invention is illustrated in the accompanying drawings, in which

50 Figure 1 is an end view of the machine,

broken away in part; Fig. 2 is a top view, the stencil-carrying drum being removed; and Fig. 3 is a detail view corresponding to Fig. 1 but showing a different position of the operating parts.

60 Referring to these drawings, the machine consists of a base A on which are mounted side-frames B, B', and a stencil-carrying drum C mounted for rotation in suitable bearings formed in the frames B, B'. The 65 drum C is of the usual construction, having a sheet of foraminated material over a portion of its periphery and means for securing the ends of a stencil-sheet to the drum so that it overlies this foraminated sheet. The shaft c 70 of the drum carries a gear-wheel c' meshing with a gear c² carried by a stub-shaft mounted for rotation in a bearing formed in the frame-plate B, which shaft also carries an operating handle c³. Directly underlying the 75 drum C is the pressure-roller D carried by arms E, E', which are loosely mounted at one end upon a shaft e journaled in suitable bearings in the side-frames. At their free ends, the arms E, E' are provided with curved 80 extensions e' (Fig. 1). A shaft e² is mounted in bearings in the side-frames and has cams e³ secured thereon in position to coact with the extensions e', so that when the shaft e² is turned by means of a suitable handle the 85 cams e³ will coact with the extensions e' to turn the arms E, E' upon the shaft e and thus lock the pressure-roller D in its inoperative position.

90 Mounted upon and extending between the side-frames B, B', is a feed-board F having a plurality of openings f therein. Suitable standards f' mounted at the sides of the feed-board F have bearings formed therein to receive the ends of the shaft f² which carries a 95 plurality of fingers f³, the end of each of these fingers being adapted to enter one of the openings f in the feed-board F. Secured to the shaft f² near one end thereof, is an arm g carrying a pin g', and a lever G has one end 100 pivoted to this arm at g' and the other end provided with an elongated slot g³ through which the shaft c of the drum C extends. Lever G carries a roller g⁴ which bears on the periphery of a cam g⁵ secured to the shaft c. 105 A coil-spring g⁶ (Fig. 2) has one end fixed to the shaft f² and the other to one of the standards f' and tends to turn shaft f² so as to carry the ends of the fingers f³ into openings f and to hold the roller g⁴ against the periph- 110

ery of the cam g^5 . The cam g^5 has a single raised portion g^7 thereon, and the half of the cam opposite this raised portion is a true semicircle. Secured on the shaft c of the drum C adjacent to the cam g^5 , is a second cam h , the periphery of which is adapted to coact with a roller h' carried by a lever H . Cam h has a single raised portion, which lies directly opposite the raised portion g^7 on the cam g^5 . This lever is also provided with a slot h^2 , through which the shaft c extends. Intermediate its ends, the lever H rests upon the pin g' carried by the arm g , and at the end opposite that carrying the roller h' lever H is provided with a tooth h^3 . Loosely mounted on one of the tie-rods h^4 connecting the side-frames of the machine, adjacent to one end thereof, is a lever K carrying at its upper end a milled pin k adapted to coact with the tooth h^3 on the lever H . At its lower end, lever K carries a pin k' which extends under one end of a lever J secured upon the shaft e . At its opposite end, the lever J carries a pin j extending over the upper edge of the arm E . Secured to the shaft e at the other side of the machine is an arm J' corresponding to the lever J and carrying a pin j' extending over the upper edge of the arm E' . In the operation of the machine as thus constructed, the shaft c is rotated, thereby rotating the stencil-carrying drum C in the direction of the arrow in Fig. 1, and also, by means of mechanism not herein shown as it forms no part of my present invention, moving the arms E , E' to carry the pressure-roller D to operative and inoperative positions. Once in each revolution of the drum C , the raised portion g^7 of the cam g^5 actuates the lever G to rock the shaft f^2 and thus raise the ends of the fingers f^3 out of the openings f and then lower them again into those openings. As shaft f^2 is thus rocked, pin g' raises the free end of lever H and then lowers the same again. If an impression-sheet be fed over the feed-board F while the ends of the fingers f^3 are raised above the surface of the feed-board to carry the edge of the impression-sheet into position to be grasped between the drum C and roller D when the latter is raised, then when the roller g^4 passes beyond the raised portion g^7 the ends of the fingers f^3 will not move downward to the position in which they are shown in Fig. 1, since they will be arrested by the impression-sheet in the position in which they are shown in Fig. 3, the impression-sheet being here indicated by the letter I . When the parts are in this position, the pin g' holds the lever H in such position that the tooth h^3 is above the upper edge of the milled pin k . As the rotation of the drum C continues, the cam h coacts with the roller h' to move the lever H to the right in Figs. 1 and 3, and on account of the elevated position in which the free end of lever H is held, the tooth h^3 will move

past the pin k without engaging the latter. During the further rotation of the drum, the impression-sheet will be grasped between it and the roller D and fed forward and imprinted upon in the usual manner. If no impression-sheet be fed over the board F , the ends of the fingers f^3 will not be arrested in their downward movement, but will be carried to the position in which they are shown in Fig. 1, thus allowing the free end of lever H to move downward to the position in which it is shown in that figure. In that case, as the cam h moves the lever H to the right in Fig. 1, the tooth h^3 will engage the pin k and rock the lever K on its pivot h^4 , the pin k' on lever K will engage the end of lever J , and the shaft e to which the lever J is fixed, will be rocked in its bearings. The pins j , j' carried by the lever J and arm J' will, during this rocking movement of the shaft e , turn the arms E , E' about the shaft e , so as to carry the pressure-roller D downwardly to inoperative position, and the roller will be held in this position until the lever H moves to the left again, after the roller h' has passed over the raised portion on the cam h . It will thus be seen that when an impression-sheet is properly fed into the machine the operation of imprinting upon the sheet is performed in the usual manner, but if no sheet be fed, the pressure-roller D is held in the depressed or inoperative position while the stencil is passing over the roller, so that the roller will not take up ink from the sheet, which, in the further operation of the machine, would be transferred to the backs of impression-sheets subsequently fed into the machine.

Having now described my invention, what I claim as new therein and desire to secure by Letters Patent is as follows:

1. In a duplicating machine, the combination of a drum, means for securing a stencil-sheet thereon, means for rotating the drum, a pressure-roller, movable arms in which said roller is rotatably mounted, said arms being movable in correspondence with the rotation of the drum to carry the pressure-roller to operative and inoperative positions relatively to the drum, a feed-board over which impression-sheets are fed between the drum and roller, and means controlled by an impression-sheet on said feed-board for operating said arms to position the pressure-roller, substantially as set forth.

2. In a duplicating machine, the combination of a drum, means for securing a stencil-sheet thereon, means for rotating the drum, a pressure-roller underlying the drum, pivoted arms in which said roller is rotatably mounted, said arms being movable about their pivots to carry the roller toward and away from the drum, a feed-board over which impression-sheets are fed between the drum and roller, and means controlled by

an impression-sheet on said feed-board for operating said arms to position the pressure-roller, substantially as set forth.

3. In a duplicating machine, the combination of a drum, means for securing a stencil-sheet thereon, means for rotating the drum, a pressure-roller underlying the drum, pivoted arms in which said roller is rotatably mounted, said arms being movable about their pivots to carry the roller toward and away from the drum, a feed-board over which impression-sheets are fed between the drum and roller, an arm movable to coact with an impression-sheet and adapted to have its movement arrested thereby, and means controlled by the arresting of the movement of said arm by the impression-sheet for operating said pivoted arms to position the pressure-roller, substantially as set forth.

4. In a duplicating machine, the combination of a drum, means for securing a stencil-sheet thereon, means for rotating the drum, a pressure roller, arms in which said roller is rotatably mounted, said arms being movable to carry the roller to operative and inoperative positions relatively to the drum, means for guiding an impression-sheet between the drum and roller, an arm movable to coact with an impression-sheet when in position for coaction with the drum and roller, and adapted to have its movement arrested thereby, and means controlled by the coaction of said arm with an impression-sheet for positioning the pressure-roller relatively to the drum, substantially as set forth.

5. In a duplicating machine, the combination of a drum, means for securing a stencil-sheet thereon, means for rotating the drum, a pressure-roller, arms in which said roller is rotatably mounted, said arms being movable to carry the roller to operative and inoperative positions relatively to the drum, a feed-board over which impression-sheets are fed between said drum and roller, said board having an opening therein, an arm mounted adjacent to the feed-board and adapted to be moved as the drum is rotated to carry its end into said opening or into coaction with an impression-sheet, and means operated when said arm enters said opening for holding the pressure-roller in inoperative position, substantially as set forth.

6. In a duplicating machine, the combination of a drum, means for securing a stencil-

sheet thereon, means for rotating the drum, a pressure-roller underlying the drum, pivoted arms in which the roller is rotatably mounted, a feed-board over which impression-sheets are fed between the drum and roller, connections between the drum and said arms for operating the latter as the drum is rotated to move the pressure-roller toward and away from the drum, and means controlled by an impression-sheet on said feed-board for making and breaking said connections, substantially as set forth.

7. In a duplicating machine, the combination of a drum, a stencil -sheet secured thereon, means for rotating the drum, a pressure-roller, arms in which the roller is rotatably mounted movable to carry the roller to operative and inoperative positions relatively to the drum, means for guiding impression sheets between the drum and roller, connections between the drum and said arms for operating the latter as the drum is rotated to move the roller relatively to the drum, and means controlled by an impression-sheet in position for coaction with the drum and roller for making and breaking said connection, substantially as set forth.

8. In a duplicating machine, the combination of a drum, a stencil -sheet secured thereon, means for rotating the drum, a pressure-roller, arms in which the roller is rotatably mounted movable to carry the roller to operative and inoperative positions relatively to the drum, a feed-board over which impression sheets are fed between the said drum and roller, said board having an opening therein, a controlling arm mounted adjacent to the feed-board and adapted to be moved as the drum is rotated to carry its end into said opening or into coaction with an impression -sheet, connections between the drum and the arms carrying the pressure-roller for operating the latter as the drum is rotated to move the roller relatively to the drum, and means operated when said controlling arm enters said opening for making and breaking said connections, substantially as set forth.

This specification signed and witnessed 105 this 17th day of July, 1907.
